UNITED STATES PATENT OFFICE.

CONRAD B. MANSBACH, OF BROCKTON, MASSACHUSETTS, ASSIGNOR OF ONE-HALF TO
FRANK L. PRICE, OF BROCKTON, MASSACHUSETTS.

INNERSOLE.

1,180,863.

Specification of Letters Patent. Patented Apr. 25, 1916.

Application filed June 29, 1915. Serial No. 36,959.

To all whom it may concern:

Be it known that I, CONRAD B. MANSBACH, a citizen of the United States, and resident of Brockton, in the county of Plymouth and State of Massachusetts, have invented certain new and useful Improvements in Innersoles, of which the following is a specification.

This invention relates to an inner sole composed of a body member usually made of leather and a facing member usually made of textile fabric, such as duck or canvas, and provided with a raised rib extending parallel with its margin and adapted to receive the inseam stitches which unite the upper, welt, and inner sole of a welted shoe, said rib being usually formed by embossing the facing member.

The invention is embodied in certain improvements in the facing member, said improvements enabling said member to be made of relatively inexpensive material, such as the waste or scraps left after cutting sheet material into relatively large forms or blanks.

Of the accompanying drawings forming a part of this specification: Figure 1 represents a side view of a blank from which the facing member embodying my invention may be cut; Fig. 2 represents an opposite side view of the blank shown by Fig. 1, portions of the pieces forming this side of the blank being broken away; Fig. 3 represents an edge view of said blank; Fig. 4 represents a side view of a completed sole; Fig. 5 represents a perspective view of a portion of the blank in the condition shown by Figs. 1, 2 and 3; Fig. 6 represents a perspective view showing a portion of the blank molded to form a lip, the trimmed edge subsequently formed being indicated by dotted lines; Fig. 7 represents a transverse section of a completed inner sole of which the facing member shown by the preceding figures forms a part, the section being on the plane of line 7—7 of Fig. 4; Fig. 8 represents a side view of one of the pieces shown by Fig. 1.

The same reference characters indicate the same or similar parts in all the views.

An inner sole of the class to which my invention relates is composed of two sole-shaped members, viz., a body member a (Fig. 7) usually made from a single sole-shaped piece of leather, and a facing member usually made from a single sole-shaped piece of duck or canvas cemented to one side

of the body member and embossed or molded to form a hollow rib extending parallel with the shank and fore part edges, and constituting an inseam stitch-engaging lip. A sole of this character is shown in my application for Letters Patent of the United States, filed March 31, 1915, Serial Number 18,259.

My present improvement is intended to reduce the cost of the fabric facing member of an inner sole of the character above described, and at the same time increase its strength and durability and enable the shank portion of the facing member to be made thicker, if desired, than the heel and fore portions.

In carrying out my invention I preferably construct the facing member as follows: From waste fragments trimmed from sheets of fabric I cut relatively small pieces or sections 12 and 13, each preferably of rectangular form and longer than the predetermined width of the facing member, so that each piece extends transversely across the facing member, the proportions of the said pieces being such that several pieces are required to form a blank of suitable length to enable a facing member to be cut therefrom. The pieces are assembled to form an elongated blank, as shown by Figs. 1 and 2, a series of pieces 12 constituting a layer forming the outer side, and a series of pieces 13 constituting another layer forming the inner side of the blank. The pieces are arranged so that one edge of each overlaps the corresponding edge of the next piece of the same series or layer.

The pieces are united, preferably by two longitudinal lines of stitches 14, although they may be united by paste or cement if desired. I prefer the stitches however on account of economy of time and labor.

The blank thus formed is embossed to form a hollow rib 15 extending parallel with the margin of the shank and fore portions and constituting an inseam stitch-receiving lip, which may be corrugated if desired, as shown in my above mentioned application. I have shown suitable means for embossing the blank in my pending application filed May 21, 1915, Serial No. 29,503. The blank is preferably embossed before it is trimmed to convert it into a sole-shaped facing member, and its area is contracted by the embossing operation, as will be seen by a compari-

son of Figs. 5 and 6. In practice the blank, after being embossed as shown by Fig. 6, is cemented to a leather blank of similar area, the two blanks being then trimmed to form 5 the sole shown by Figs. 4 and 7.

The joints formed by the overlapping portions of the pieces 12 alternate with the joints formed by the overlapping portions of the pieces 13, as shown by Fig. 3, so that 10 the thickened portions formed by said joints are spaced apart, especially at the fore portion, excessive thickness at any one locality being avoided. I prefer however to increase the width of the overlapping portions of the 15 inner pieces 13 at the shank portion of the sole, so that the portion of the facing member between the lines $x-x$ and $y-y$ (Fig. 3) constitutes an elongated shank portion of uniform maximum thickness and stiffness, it being desirable to make the shank portion of the 20 completed sole stiffer than the fore and heel portions.

When the inner sole is being secured to the welt and upper of a welted shoe by inseam 25 stitches passing through the rib or lip 15, a guide on the stitching machine bears on the facing member of the inner sole at the angle formed by the inner side of the lip and the surface of the facing member bounded thereby. To prevent said guide from engaging 30 the exposed edges of the pieces 12 and lifting said edges, I cause the exposed edges at one side of the median line of the sole to face oppositely from the exposed edges at the other side of said median line, so that the feeding movement of the sole indicated by 35 the arrows (Fig. 6) during the stitching operation, will cause the said exposed edges to slide by the guide without being caught and raised thereby. To this end I cut a slit 18 40 in one end of each piece 12, and insert the corresponding edge of the next piece in the slit so that two oppositely facing edge portions are provided, one at one side, and the 45 other at the opposite side, of the median line of the sole.

It will be seen that by making the facing

Copies of this patent may be obtained for five cents each, by addressing the "Commissioner of Patents, Washington, D.C."

member of an inner sole of waste pieces, the cost of manufacture is materially reduced, and at the same time the strength and durability of the sole and its stiffness at the shank portion are greater than would be the case if the facing member were made from a single layer or piece of fabric. The joints formed by the overlapping portions of the pieces extending transversely of the sole form a plurality of reinforced portions preventing the facing member from stretching crosswise. 50 55

Having described my invention, I claim:

1. An inner sole having a pieced facing member composed of a plurality of series of pieces of waste flexible moldable material, each series forming a layer having overlapping edges extending transversely of the sole and united to form a plurality of reinforced portions preventing the facing member from stretching crosswise, the reinforced portions of one layer alternating with those of the next layer to prevent excessive thickness at any one locality, the pieces being suitably 60 65 united and the member molded to form a rib.

2. An inner sole having a pieced member composed of pieces of waste material having overlapping edges extending transversely of the sole and including a plurality of pieces, 75 each having a central slit in one of its transverse edges, and receiving an edge of the adjoining piece whereby the exposed edges of the overlapping portions at one side of the median line of the sole are caused to face oppositely from the exposed edges at the other side of said line, the pieces being suitably 80 85 united.

3. An inner sole having a pieced member composed of an inner and an outer series of pieces of waste material having overlapping edges extending transversely of the sole, the pieces of material at the shank being overlapped a greater distance to form a relatively thick shank portion.

In testimony whereof I have affixed my signature.

CONRAD B. MANSBACH.
